(57) **CLAIM**

The ornamental design for a pouch for a collectible card protector, as shown and described.

DESCRIPTION

FIG. 1 is a front elevation view of my new design for a pouch for a collectible card protector;

FIG. 2 is a rear elevation view thereof;

FIG. 3 is a left side elevation view thereof, the right side elevation view being a mirror image;

FIG. 4 is a top plan view thereof; and,

FIG. 5 is a bottom plan view thereof.

The stippling represents shading; the lines inwardly of edges of the pouch and the broken lines about the transparent windows represent stitching.
